UNITED STATES PATENT OFFICE.

GEORGE R. WILLIAMS, OF FINDLAY, OHIO.

MOLDING-MACHINE.

No. 839,244.

Specification of Letters Patent.

Patented Dec. 25, 1906.

Application filed April 12, 1905. Serial No. 265,218.

To all whom it may concern:

Be it known that I, GEORGE R. WILLIAMS, a citizen of the United States, residing at Findlay, in the county of Hancock and State 5 of Ohio, have invented a new and useful Molding-Machine, of which the following is a specification.

This invention relates more particularly to means for forming molds for metal castings.

One of the principal objects is to provide a novel machine of a comparatively simple nature wherein the weight placed upon the movable parts is substantially balanced, so that lateral or side strains are to a great extent avoided, thereby eliminating abnormal binding and wearing action between the elements and maintaining the same in proper relation, thus securing high-grade molds, and consequently correspondingly perfect castings.

Another object is to provide a structure wherein the important working parts and bearings are housed and protected against the entrance of sand, thereby preventing the 25 wearing and consequent looseness of said bearings from this cause.

A still further and important object is to provide novel flask-elevating means which act in conjunction with the pattern-moving 30 means and effect the detachment of the flask-section from its positioning means when the pattern is drawn from the mold.

The preferred embodiment of the invention is illustrated in the accompanying drawings and is described in the following specification.

An inspection of the claims hereto appended will clearly indicate that the invention is not limited solely to the structure herein set 40 forth.

In said drawings, Figure 1 is a view, partly in elevation and partly in section, of the machine complete and showing a set or gate of patterns and stripper-plate therefor located on said machine. Fig. 2 is a view in elevation of a portion of the machine, the side opposite to that shown in Fig. 1 being illustrated. Fig. 3 is a horizontal sectional view on the line 3-3 of Fig. 2. Fig. 4 is a top plan 45 view of the upper portion of the machine. Fig. 5 is an end elevation of the cross-head and a portion of the crank device detached therefrom.

Similar reference-numerals designate corresponding parts in all the figures of the 55 drawings.

In the embodiment illustrated a tubular standard 6 is employed mounted on a base comprising feet 7, radiating from the lower end of the standard and preferably downwardly inclined, as shown in Fig. 1. Upon the upper end of the said tubular standard is located a spider having radiating arms 8, carrying bosses 9 at their outer ends, in which are secured upright guide-pins 10. 60 This structure constitutes a support for the stripper-plates, one of which is shown at 11, and therefore constitutes also a support for the flask-sections that are placed upon the stripper-plate 11 in the well-known manner 65 and are suitably secured in place—as, for instance, by having pins adapted to engage in sockets 12 located in the opposite margins of the plate 11.

Movable pattern-supporting means are 75 employed, consisting of a spider-frame 13, mounted upon the upper end of a vertical stem 14, that is slidably mounted in the tubular standard. The spider-frame 13 has radiating arms 15, provided at their outer 80 ends with guide-collars 16, slidably mounted on the pins 10 and connected by braces 17. This spider thus movably supports a pattern-plate 18, that carries a set or gate of patterns—as, for instance, 19—which patterns slidably 85 pass through the stripper-plate 11 in the ordinary manner. Interposed between the pattern-plate and guide 16 are detachable bushings 20, arranged to receive the wear of the parts. Thus when these bushings become worn they may be removed and substituted by new ones in order to maintain the pattern-plate in parallel relation to the stripper-plate.

The sliding stem 14 is guided in a suitable 95 collar 21, fixed within the upper portion of the tubular standard, and said stem carries at its lower end a cross-head 22, provided with a guideway 23, that is thus disposed transversely of the stem and of its path of movement, this guideway being formed of spaced sets of tracks 24, the lowermost of which are spaced apart, as illustrated in Fig. 5. The ends of the cross-head 22 are slidably located in guide slots or openings 25 in 100 the opposite sides of the tubular standard,

and these openings, as well as the ends of the cross-head, are covered by a casing-section 26, surrounding the standard 6 and vertically slidably thereon, being ordinarily held against movement, however, by clamping split-ring portions 27, located at its upper and lower ends. The adjustment of the casing-section 26 is secured by a screw 28, having a cone-bearing 29 at its lower end with one of the 10 feet 7 of the standard, the upper end having a threaded engagement in an ear 30, carried by the lower ring portion 27. It will thus be seen that upon loosening the ring portions 27 and turning the screw 28 the casing-sections 26 can be raised or lowered and can be clamped in any desired position by means of said ring portions.

The casing-section constitutes means for supporting the actuating mechanism of the 20 pattern-carrying means, and said mechanism consists of a rock-shaft 31, journaled in the lower portion of the casing-section 26 at one side of the standard and having secured to an exposed end thereof an operating-lever 32. Secured to the rock-shaft 31 within the casing-section is a crank device in the form of an arm 33, disposed in angular relation to the lever 32 and having rollers 34 journaled on its free end, which rollers operate in the 30 guideway 23 of the cross-head 22 and against the tracks 24 thereof. It will thus be seen that when the lever is in the position shown in Fig. 1 the stem 14 will be elevated and the patterns 19 thus projected through the stripper-plate 11. On the other hand, when said lever is swung to a position to carry the rollers 34 toward the opposite end of the guideway, the patterns will be moved downwardly through the stripper-plate.

40 For the purpose of elevating the flask-section when the patterns are drawn from the mold the following mechanism is employed: Upright rods 35 are slidably mounted on opposite sides of the standard 6 and have their 45 upper ends forked, as shown at 36, the upper terminals of these branches or forks slidably passing through openings 37 in the opposite margins of the stripper-plate 11. Journaled in the lower portion of the casing-section 26 50 and on the opposite side of the standard to the rock-shaft 31 is another rock-shaft 38, carrying crank-arms 39, that engage beneath shoulders or annular flanges 40, formed upon the rods 35. Secured to one end of the rock-shaft 38 is a crank-arm 41, having a longitudinally-disposed slot 42, and in this slot is adjustably mounted a pivot-bolt 43, connected to one end of a link 44, the other end of the 55 link being pivoted, as shown at 45, to the operating-lever 32. A counterbalancing-weight 46 is adjustably mounted on an arm 47 and is also connected to the rock-shaft 38.

It is believed that the operation of the machine can now be made clear. The desired 60 set of patterns are properly mounted on the

supporting-spider 13 and the coacting stripper-plate placed upon the ends of the pins or posts 10. The patterns are then elevated through the stripper-plate by swinging the lever 32 to the position shown in Fig. 1, 70 whereupon the upper ends of the fingers or forks 36 are disposed so that they are substantially flush with the upper surface of the stripper-plate. The flask-section is placed upon the stripper-plate and is positioned in 75 the usual manner, after which said section is filled with sand and rammed. Then the lever is swung in an opposite direction, thereby depressing the stem 14 and drawing the patterns from the molds downwardly through 80 the stripper-plate. At the same time the rods 35 are elevated, and consequently the flask-section is lifted from the stripper-plate and from its interlocking engagement therewith. Said flask-section is thereupon removed. The other half is put in place and the operation repeated, (provided both sides of the casting are to be alike.)

It is to be noted that in this machine the lifting mechanism and operating means 90 therefor are centrally disposed beneath the mold, thereby obviating side or binding strains and limiting to a material degree the danger of abnormal wear with a consequent looseness of parts and inaccuracy of operation. This same advantage is furthered, 95 moreover, by housing the parts and bearings in the tubular standard and the casing-section, so that said bearings are protected from the sand and grit. Furthermore, novel and 100 simple means are provided for elevating the flask-sections from the stripper-plate and from their interlocking engagements therewith, so that the danger of tearing and breaking the molds is reduced to a minimum.

105 From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

110 Having thus described my invention, what I claim as new, and desire to secure by Letters Patent, is—

1. In a molding-machine, the combination with a tubular standard forming an inclosed chamber, of guides mounted on and projecting above the upper end of the standard, a pattern-supporting stem slidably mounted in the standard and projecting above the same between the guides, said stem also having a portion movably located in the inclosed chamber, pattern-carrying means mounted on the upper exposed end of the standard and slidably engaging the guides, a rock-shaft journaled transversely in the standard 125 130

and having a portion located in the inclosed chamber and a portion disposed exteriorly of the standard, a connection between said inclosed portion of the shaft and stem, said connection being also located in the inclosed chamber, and operating means connected to the exposed portion of the shaft.

2. In a molding-machine, the combination with a tubular standard forming an inclosed chamber, of a spider mounted on the upper end of the standard and carrying guides, said guides constituting supports for a stripper-plate, a stem slidably mounted in the standard and having a portion movable in the inclosed chamber thereof, said stem also having a spider at its upper end located above the standard and slidably engaging the guides, said latter spider constituting a pattern-support, an actuating rock-shaft journaled on the standard and projecting into the inclosed chamber, and a movable connection between the inclosed portions of the rock-shaft and the stem, said connection being also located in the inclosed chamber and thus housed within the standard.

3. In a molding-machine, the combination with flask-supporting means having a guide, of pattern-supporting means movable with respect to the flask-supporting means and including a guide element disposed transversely of the line of movement of said pattern-supporting means and movably engaging in the guide of the flask-supporting means, and means engaging said guide of the pattern-supporting means to move the same, said moving means operating in the guide transversely of the line of movement of the pattern-supporting means.

4. In a molding-machine, the combination with flask-supporting means including a standard having a guide, of pattern-supporting means movable with respect to the flask-supporting means and including a stem having a transverse guide that movably engages in the guide of the standard, and means engaging the guide of the stem to move the same and thereby the pattern-supporting means.

5. In a molding-machine, the combination with flask-supporting means including a standard having guide openings or slots, of pattern-supporting means including a stem slidably mounted in the standard and having a cross-head that slidably engages in the openings or slots, and means movably engaging the cross-head for effecting the movement thereof and of the pattern-supporting means.

6. In a molding-machine, the combination with flask-supporting means including a tubular standard having oppositely-disposed guide openings or slots, of pattern-supporting means including a stem slidably mounted in the standard, a cross-head carried by the lower end of the stem and operating in the

guide openings or slots of the standard, a rock-shaft journaled on the standard, and a crank device carried by the rock-shaft and engaging the cross-head to move the same.

7. In a molding-machine, the combination with flask-supporting means, of pattern-supporting means including an upright stem slidably mounted on the flask-supporting means and having a transversely-disposed guideway, a rock-shaft journaled on the flask-supporting means and out of upright alignment with the stem, and a crank secured to the rock-shaft and having a bearing in the guideway of the stem.

8. In a molding-machine, the combination with a tubular standard, of a spider carried by the upper end of the same and having guides, another spider slidably mounted on the guides, a stem slidably mounted in the standard and connected to the latter spider, a cross-head carried by the lower end of the stem and located within the tubular standard, said cross-head having a guideway disposed transversely of the stem and standard, a rock-shaft journaled on the standard, a crank device carried by the rock-shaft and having its free end movably engaging in the guideway of the cross-head, and means for actuating the rock-shaft.

9. In a molding-machine, the combination with a tubular standard having an opening in its side, of movable pattern-supporting means including a stem slidably mounted in the standard, a casing-section surrounding the standard and covering the opening, a rock-shaft journaled in the casing-section and having portions located therein, and a crank device carried by the portion of the rock-shaft that is in the casing, said crank device operating through the opening in the standard and engaging in the guideway of the stem.

10. In a molding-machine, the combination with a tubular standard having an opening in its side, of movable pattern-supporting means including a device slidably mounted in the standard, mechanism for actuating the pattern-supporting means, said mechanism passing through the opening in the standard and engaging said slidably device, and means mounted on the standard for supporting the actuating mechanism thereon, said means constituting a closure-section for the standard-opening.

11. In a molding-machine, the combination with a tubular standard having an opening in its side, of movable pattern-supporting means including a device slidably mounted in the standard, a casing-section mounted on the standard and covering the opening, and mechanism for actuating the pattern-supporting means, said mechanism being carried by the casing-section and furthermore passing through the standard-opening and engaging the said slidably device.

12. In a molding-machine, the combination with a tubular standard having an opening in its side, of movable pattern-supporting means including a stem slidably mounted in the standard and having a transverse guideway at its lower end, a casing-section surrounding the standard and covering the opening, a rock-shaft journaled in the casing-section, and a crank device carried by the rock-shaft, said crank device operating through the opening in the standard and engaging in the guideway of the stem.

13. In a molding-machine, the combination with a tubular standard having guide-openings in opposite sides, of movable pattern-supporting means including a stem slidably mounted in the standard, a cross-head carried by the stem and slidably engaging in the guide-openings of the standard, a casing-section mounted on the standard and covering the openings, a rock-shaft journaled in the casing-section, an actuating-lever connected to the rock-shaft, and a movable connection between the rock-shaft and the cross-head.

14. In a molding-machine, the combination with a tubular standard having an opening in its side, of movable pattern-supporting means including a device slidably mounted in the standard, mechanism for actuating the pattern-supporting means, said mechanism operating through the opening in the standard and engaging said slideable device, and means adjustably mounted on the standard for supporting said actuating mechanism.

15. In a molding-machine, the combination with a tubular standard having an opening in its side, of movable pattern-supporting means including a device slidably mounted in the standard, a casing-section adjustably mounted on the standard and covering the opening, and mechanism for actuating the pattern-supporting means, said mechanism being carried by the adjustable casing-section and engaging the said slideable device.

16. In a molding-machine, the combina-

tion with a tubular standard having an opening in its side, of movable pattern-supporting means including a device slidably mounted in the standard, a casing-section adjustably mounted on the standard and covering the opening, mechanism for actuating the pattern-supporting means, said mechanism being carried by the adjustable casing-section and engaging the said slideable device, and means for adjusting the casing-section on the standard.

17. In a molding-machine, the combination with a base, of a tubular standard mounted thereon and having openings in its side, movable pattern-supporting means including a stem slidably mounted in the standard, a casing-section slidably mounted on the standard and covering the opening, a rock-shaft journaled in the casing-section, a connection between the rock-shaft and the stem, said connection operating through the standard-opening, and means for adjusting the casing upon and holding the same against movement with respect to the standard, said means including a screw interposed between the base and casing.

18. In a molding-machine, the combination with a standard, of a casing-section adjustably mounted thereon, separate rock-shafts journaled on the section, pattern-elevating means slidably mounted on the standard and operated from one of the rock-shafts, flask-elevating means slidably associated with the standard and operated from the other shaft, a lever connected to one of the shafts, a crank connected to the other shaft, and a link connection between the crank and lever.

In testimony that I claim the foregoing as my own I have hereto affixed my signature in the presence of two witnesses.

GEORGE R. WILLIAMS.
